CONVERSION OF HYDROCARBON OILS

Jacob Benjamin Heid, Chicago, Ill., assignor to
 Universal Oil Products Company, Chicago, Ill.,
 a corporation of Delaware

Application May 24, 1935, Serial No. 23,219
 Renewed May 15, 1939

3 Claims. (Cl. 196—49)

This invention refers to an improved process for the pyrolytic cracking of hydrocarbon oils for the production, primarily, of high yields of desirable light distillate such as motor fuel of good anti-knock value, wherein the charging stock is subjected to relatively mild cracking, the intermediate liquid products of the process subjected to further cracking within the same system under more severe conditions than those to which the charging stock is subjected while the residual liquid conversion products from both cracking stages are also subjected to further cracking and coking under independently controlled conditions within the same system.

In one embodiment the invention comprises subjecting hydrocarbon oil charging stock for the process to relatively mild cracking conditions of elevated temperature and superatmospheric pressure in a heating coil, separating the resulting vaporous and liquid conversion products, subjecting the vapors to fractionation whereby their insufficiently converted components are condensed as reflux condensate, subjecting fractionated vapors of the desired end-boiling point to condensation, recovering the resulting distillate, subjecting the reflux condensate to independently controlled conversion conditions of higher cracking temperature and superatmospheric pressure in a separate heating coil and communicating reaction chamber, separately withdrawing vaporous and liquid conversion products from said reaction chamber, commingling the vaporous conversion products from the reaction chamber with the conversion products from the first mentioned heating coil, prior to the fractionation of the vaporous components of the latter, subjecting the residual liquid withdrawn from the reaction chamber together with residual liquid from the first mentioned cracking stage to further cracking in a separate heating coil under non-coking conditions, introducing the resulting highly heated products into a coking chamber wherein their reduction to substantially dry coke is accomplished, subjecting vaporous products from the coking chamber to fractionation for the formation of reflux condensate, returning the reflux condensate for further conversion to the same heating coil to which the reflux condensate from the first mentioned cracking step is supplied, subjecting fractionated vapors of the desired end-boiling point from the last mentioned fractionating stage to condensation and recovering the resulting distillate.

The accompanying diagrammatic drawing illustrates one specific form of apparatus in which the invention may be carried out.

Referring to the drawing, hydrocarbon oil charging stock for the process, which may be any desired type of oil but is normally an oil of relatively wide boiling range or of relatively high-boiling characteristics, is supplied through line 1 and valve 2 to pump 3 by means of which it is fed through line 4 and valve 5 into heating coil 6. The charging stock may, of course, be pre-heated, when desired, in any well known manner not illustrated, prior to its introduction into the heating coil.

A furnace 7 of any desired form supplies the required heat to the oil passing through heating coil 6 to subject the same to the desired cracking temperature, preferably at a substantial superatmospheric pressure and the heated products are discharged from the heating coil through line 8 and valve 9 into separating chamber 10.

Chamber 10 is preferably operated at a substantially reduced pressure relative to that employed in heating coil 6 in order to increase the degree of vaporization therein but may, when desired, be operated at substantially the same pressure as that employed at the outlet from the heating coil. Separation of vaporous and liquid conversion products is accomplished in chamber 10, the latter being withdrawn from the lower portion of this zone through line 11 and valve 12 to pump 13 by means of which it is supplied through line 14 and valve 15 to heating coil 16 for further treatment, as will be later more fully described.

In the case here illustrated separating chamber 10 comprises the lower portion of column 17, the upper portion of which comprises fractionator 18, and the vaporous conversion products from chamber 10 pass through a suitable partition or deck 19 into the fractionator wherein their components boiling above the range of the desired light distillate product of this stage of the process are condensed as reflux condensate.

Fractionated vapors of the desired end-boiling point are withdrawn, together with uncondensable gas produced by the operation, from the upper portion of fractionator 18 through line 20 and may be directed through valve 21 in this line to condensation and cooling in condenser 22. The resulting distillate and gas passes through line 23 and valve 24 to collection and separation in receiver 25. Uncondensable gas may be released from the receiver through line 26 and valve 27. Distillate may be withdrawn from receiver 25 through line 28 and valve 29 to storage or to any desired further treatment. When desired, a regulated portion of the distillate collected in receiver 25 may be recirculated by well 55

known means, not shown in the drawing, to the upper portion of fractionator 18 to serve as a cooling and refluxing medium in this zone. It is also within the scope of the invention, when desired, instead of subjecting the fractionated vapors from fractionator 18 to condensation and collection, in the manner described, to divert the same from line 20 through line 30 and valve 31 into fractionator 59 wherein they may commingle with the other vaporous conversion products of the process and be subjected to fractionation therewith to be finally recovered, all or in part, together with the light distillate products of the process.

15 The reflux condensate formed in fractionator 18 may be withdrawn from the lower portion of this zone through line 33 and valve 34 to pump 35 by means of which it is supplied through line 36, valve 37 and line 38 to heating coil 39 for further cracking.

20 Heating coil 39 is located within a furnace 40 of any suitable form by means of which the oil supplied to this zone is subjected to the desired cracking conditions of elevated temperature and 25 superatmospheric pressure and the heated products are discharged from heating coil 39 through line 41 and valve 42 into a reaction chamber 43.

25 Chamber 43 is also preferably maintained at a substantial superatmospheric pressure and, although not indicated in the drawing, this zone is 30 preferably insulated in order that cracking of the heated products supplied thereto and particularly their vaporous components may continue in the reaction chamber. Separation of vaporous and 35 liquid conversion products is accomplished in chamber 43 and the vaporous conversion products may be withdrawn in the case here illustrated from the lower portion of the chamber above the point of removal of the liquid conversion 40 products, although they may be removed at any desired point or plurality of points in the reaction chamber, and are directed through line 44, valve 45 and line 8 into separating chamber 10.

45 Liquid conversion products are withdrawn from the lower portion of chamber 43 through line 46 and valve 47 to pump 48 by means of which they are directed through line 49, valve 50 and line 14 to further treatment in heating coil 16 together with the liquid conversion products 50 from chamber 10, which are supplied to this zone as previously described.

55 Heating coil 16 is located within a furnace 51 and although the heating coil and furnace are illustrated in a conventional manner in the drawing they are preferably of such design (several forms of which are now well known in the art) that the relatively heavy oils supplied thereto are quickly heated to the desired cracking temperature without allowing the oil to remain in the 60 heating coil and communicating lines for a sufficient length of time to permit any excessive formation and deposition of coke therein. This method of heating ordinarily involves the use of relatively high oil velocities and relatively high 65 rates of heating in the heating coil and in the preferred embodiment of the present invention the relatively heavy oils supplied to heating coil 16 are subjected therein to a temperature sufficient to effect their subsequent reduction to substantially dry coke in coking chamber 54, to 70 which they are supplied from heating coil 16 through line 52 and valve 53.

75 Coking chamber 54 is preferably maintained at substantially atmospheric or a relatively low superatmospheric pressure, although higher pres-

sures up to several hundred pounds per square inch may be employed in this zone, when desired. Coke produced in chamber 54 may be allowed to accumulate in this zone to be removed therefrom in any suitable well known manner, not illustrated, when the chamber has been substantially filled with coke or after its operation is completed for any other reason. It will be understood, of course, that although only one coking chamber is shown in the drawing two or more such zones 10 may be employed, when desired, in which case they preferably are alternately operated, cleaned and prepared for further operation in order that the coking stage of the system may be operated continuously. Chamber 54 is provided with a 15 suitable drain-line 55 controlled by valve 56 which may also serve as a means of introducing steam, water or any other suitable cooling medium into the chamber after its operation has been completed and preferably after it has been isolated 20 from the rest of the system in order to hasten cooling and facilitate the removal of coke therefrom.

25 Vaporous products are withdrawn from the upper portion of chamber 54 through line 57 and valve 58 and are subjected to fractionation in fractionator 59 wherein their components boiling above the range of the desired final light distillate product of this stage of the process are 30 condensed as reflux condensate. The reflux condensate is withdrawn from the lower portion of fractionator 59 through line 60 and valve 61 to pump 62, by means of which it is returned through line 63 and valve 64 to further cracking 35 in heating coil 39, together with the reflux condensate from fractionator 18, which is supplied to this zone in the manner previously described.

40 Fractionated vapors of the desired end-boiling point are withdrawn from the upper portion of fractionator 59 through line 65 and valve 66 and are subjected to condensation and cooling in condenser 67. The resulting distillate and gas passes 45 through line 68 and valve 69 to collection and separation in receiver 70. Uncondensable gas may be released from the receiver through line 71 and valve 72. Distillate may be withdrawn from receiver 70 through line 73 and valve 74 to storage or to any desired further treatment. When 50 desired, a regulated portion of the distillate collected in receiver 70 may be recirculated by well known means, not shown in the drawing, to the upper portion of fractionator 59 to serve as a cooling and refluxing medium in this zone.

55 In a process such as illustrated and above described, the preferred operating conditions may be approximately as follows: The heating coil to which the charging stock is supplied may utilize an outlet cracking temperature ranging, for example from 800 to 950° F., or thereabouts, preferably with a superatmospheric pressure at this 60 point in the system of from 100 to 500 pounds, or thereabouts, per square inch. The succeeding separating chamber is preferably operated at a substantially reduced pressure relative to that employed in the heating coil although, when desired, this zone may be operated at a substantial superatmospheric pressure up to substantially the same as that employed in the heating coil. The fractionating, condensing and collecting equipment of this stage of the system may be operated 65 at substantially the same or somewhat lower pressures than that employed in the separating chamber. The heating coil to which the reflux condensates from both fractionators of the system is supplied may utilize a cracking tempera- 70 75

ture, measured at the outlet therefrom, ranging, for example, from 850 to 975° F., or thereabouts, preferably with a superatmospheric pressure at this point in the system of from 100 to 500 pounds 5 or more per square inch. A substantial superatmospheric pressure substantially the same as that employed in the reflux heating coil or somewhat reduced relative thereto may be utilized in the succeeding reaction chamber. The heating 10 coil to which residual liquid conversion products from the charging stock and reflux cracking stages of the system are supplied may employ an outlet cracking temperature ranging, for example, from 900 to 1050° F., with a superatmospheric 15 pressure which may range from slightly above atmospheric pressure to 300 pounds, or thereabouts, per square inch. The coking chamber may employ any desired pressure ranging from substantially the same as that in the preceding 20 heating coil down to substantially atmospheric pressure and the pressure employed in the coking chamber may be substantially equalized or somewhat reduced in the succeeding fractionating, condensing and collecting equipment.

25 As a specific example of the operation of the process of the invention, the charging stock, which comprises a 30° A. P. I. gravity Mid-Continent topped crude, is subjected in the heating coil to which it is supplied to an outlet cracking 30 temperature of approximately 900° F., at a superatmospheric pressure of about 300 pounds per square inch and the heated products are introduced into a separating chamber operated at a superatmospheric pressure of about 50 pounds 35 per square inch. Liquid conversion products are withdrawn from the separating chamber and supplied to a separate heating coil. The vaporous conversion products from the separating chamber are subjected to fractionation for the formation 40 of reflux condensate and the recovery of motor fuel fractions having an end-boiling point of approximately 300° F. The liquid conversion products from the separating chamber are quickly heated, together with liquid conversion 45 products from the high-pressure reaction chamber of the system, in the separate heating coil to which these materials are supplied, to an outlet cracking temperature of approximately 970° F., at a superatmospheric pressure of about 75 50 pounds per square inch and the highly heated materials are introduced into a coking chamber maintained at substantially the same pressure, wherein they are reduced to coke. Vaporous products from the coking chamber are separately 55 subjected to fractionation for the formation of reflux condensate and the recovery of motor fuel having an end-boiling point of approximately 400° F. The reflux condensates from both fractionators are supplied to a separate heating coil 60 wherein this material is subjected to a cracking temperature, measured at the outlet therefrom, of approximately 940° F., at a superatmospheric pressure of about 350 pounds per square inch and the heated products are introduced into a reaction chamber maintained at substantially the same pressure. Residual liquid 65 withdrawn from the reaction chamber is supplied, as previously mentioned, to the same heating coil as the residual liquid from the separating chamber of the first cracking stage and vaporous conversion products separately withdrawn from the reaction chamber are supplied to the separating chamber. This operation will produce, 70 per barrel of charging stock, approximately 64 75 percent of motor fuel having an octane number

of approximately 70 and approximately 80 pounds of good quality low volatile coke, the remainder being chargeable, principally to uncondensable gas.

1 claim as my invention:

1. A process for the pyrolytic conversion of hydrocarbon oils which comprises subjecting hydrocarbon oil charging stock for the process to pyrolytic conversion conditions of cracking temperature and superatmospheric pressure in the 10 heating coil, introducing the resulting heated products into a reduced pressure separating chamber wherein separation of vaporous and liquid conversion products is accomplished, subjecting the vaporous conversion products to fractionation for the formation of reflux condensate, recovering a desirable light distillate from the fractionated vapors by condensation, subjecting the reflux condensate to independently controlled conversion conditions of higher cracking temperature and superatmospheric pressure in a 15 heating coil and communicating reaction chamber, separating the vaporous and liquid conversion products in said reaction chamber, removing vaporous conversion products therefrom and 20 introducing the same into said reduced pressure separating chamber, separately removing the liquid conversion products from the reaction chamber, commingling the same with liquid conversion products withdrawn from said reduced 25 pressure separating chamber and heating the commingled materials to a high conversion temperature under non-coking conditions in a separate heating coil, introducing the heated materials from said separate heating coil into a low- 30 pressure coking chamber and reducing same therein to coke, subjecting vaporous products from the coking chamber to fractionation in a separate fractionating zone for the formation of reflux condensate, returning the reflux condensate from the last mentioned fractionating stage 35 to further conversion in the same heating coil to which the reflux condensate from the first mentioned fractionating stage is supplied, subjecting fractionated vapors of the desired end-boiling point from the said last mentioned fractionating stage to condensation and recovering 40 the resulting distillate.

2. A process for the pyrolytic conversion of hydrocarbon oils which comprises subjecting hydrocarbon oil charging stock for the process to pyrolytic conversion conditions of cracking temperature and superatmospheric pressure in a heating coil, introducing the resulting heated products into a reduced pressure separating 45 chamber wherein separation of vaporous and liquid conversion products is accomplished, subjecting the vaporous conversion products to fractionation for the formation of reflux condensate, recovering a desirable light distillate from the fractionated vapors by condensation, subjecting the reflux condensate to independently controlled conversion conditions of higher cracking temperature and superatmospheric pressure in a heating coil and communicating reaction chamber, 50 separating the vaporous and liquid conversion products in said reaction chamber, removing vaporous conversion products therefrom and introducing the same into said reduced pressure separating chamber, separately removing the liquid conversion products from the reaction chamber, commingling the same with liquid conversion products withdrawn from said reduced 55 pressure separating chamber and heating the commingled materials to a high conversion tem- 60

70

75

perature under non-coking conditions in a separate heating coil, introducing the heated materials from said separate heating coil into a low-pressure coking chamber and reducing same 5 therein to coke, subjecting vaporous products from the coking chamber to fractionation and returning resultant reflux condensate to the second-mentioned heating coil for further treatment therein together with the first-named reflux condensate.

3. A hydrocarbon oil conversion process which comprises heating topped crude oil to cracking temperature under pressure in a first heating coil and separating the same into vapors and 10 unvaporized oil in a separating chamber, fractionating the vapors and subjecting resultant reflux condensate to independently controlled cracking conditions in a second heating coil,

introducing the heated reflux condensate into a second chamber maintained at cracking temperature and under higher pressure than the first-mentioned chamber, separating the resultant conversion products into vapors and residual 15 liquid and combining the former with the first-mentioned vapors for fractionation therewith, commingling the residual liquid with unvaporized oil from the first-mentioned chamber and heating the mixture to coking temperature under 20 pressure in a third heating coil, reducing the heated mixture to coke in a third chamber, fractionating vapors evolved in the third chamber independently of the first and second-mentioned vapors and supplying reflux condensate thus 25 formed directly to said second coil, and finally condensing the fractionated vapors.

JACOB BENJAMIN HEID.
